MOTORCYCLE CONTROL LEVER DUST SHIELD

Victor Alan Boocock, 757 Harvard Ave.,
Menlo Park, Calif. 94025

Filed Jan. 12, 1970, Ser. No. 20,897

Term of patent 14 years

Int. Cl. D12—14

U.S. CL. D90—1

Fig. 4

Fig. 5

FIG. 1 is a plan view of a motorcycle control lever dust shield showing my new design;

FIG. 2 is a side view of the dust shield shown in FIG. 1 taken from the left;

FIG. 3 is a plan view of the dust shield like FIG. 1, but taken from the opposite side;

FIG. 4 is an end view taken in the direction of the arrows 4—4 of FIG. 1; and

FIG. 5 is an end view taken in the direction of the arrows 5—5 of FIG. 3.

The control lever, cable and hand grip shown in broken lines are included for illustrative purposes only.

I claim:

The ornamental design for a motorcycle control lever dust shield, as shown and described.
